METAL SPRAY GUN OF THE WIRE FEED
TYPE

Arthur P. Shepard, Flushing, and Herbert S. Ingham, Queens Village, N. Y., assignors to Metallizing Engineering Co. Inc., Long Island City, N. Y., a corporation of New Jersey

Original application December 1, 1941, Serial No. 421,196. Divided and this application July 15, 1943, Serial No. 494,810

8 Claims. (Cl 253—59)

This invention relates to new and useful improvements in metal spray guns of the wire feed type.

Metal spray guns of the wire feed type are devices in which a metal rod or wire is continuously fed into a melting zone, from which zone the metal is propelled in finely subdivided form by suitable means such as a blast of air or other gas. The rod or wire is fed into the melting zone by suitable rod or wire feeding means, such as knurled burs pressing against opposite sides of the wire. These wire or rod feeding means are driven, preferably operating through reduction gears, by a compressed gas motor, i. e., a motor, the rotor of which is rotated by the force of compressed gas. The load on the motor varies from time to time due to the changes in the position of the operator, kinks in the wire, etc. Since it is essential for successful spraying operations that the ratio of feed of the wire be uniformly maintained, it is likewise essential that the motor have a comparatively stable speed of operation, i. e., that its speed of operation be affected as little as possible by variations in the load. One common form of compressed gas motor is a compressed gas turbine and our invention shall be hereinafter described by way of illustration but not of limitation in connection with metal spray gun constructions of the wire feed type having a compressed gas turbine.

In the operation of metal spray guns, it is necessary to maintain different rates of feed when spraying different metals. For example, low melting point metals may be fed and sprayed more rapidly than higher melting point metals and larger diameter wires must be fed and sprayed more slowly than smaller diameter wires of the same material.

It is the usual practice to attempt the approximation of the proper conditions for the particular metal to be sprayed by providing for replaceable gearing designed to permit the gun to be operated at the required rate of wire feed and to permit the turbine to operate within a range of stable operation. Changing the gearing, however, involves loss of time and the possibility that metal particles will be picked up by the gears in handling and interfere with the operation of the gun. When attempting to eliminate gear changes by reducing the turbine speed through a throttling of the blast gas supply, the turbine becomes unstable and a uniform wire feed is no longer maintained as the then available power is insufficient to compensate for load increases.

This operating instability of the ordinary gas

blast operated turbine particularly at lower speeds, has been a serious disadvantage in metal spray gun constructions hitherto used. Although it may be possible in a given case to maintain a satisfactory wire feed, the ordinary gas turbine is very susceptible to variations in the operating load. The ordinary gas turbine has sufficient power for feeding the wire under normal conditions as long as a sufficient quantity of gas is supplied to the turbine rotor at a sufficiently high pressure. The power requirements of the turbine, however, necessitate the feeding thereto of sufficient impelling gas to cause the turbine to operate at a very high speed. At whatever speed, however, the turbine operates with a given inflow and pressure of gas, all the power is used up and no excess power is available to take care of variations in the operating load.

The governing mechanism in accordance with 20 the invention is variably adjustable to procure different operating speeds and yet is capable at any given speed to make excess power practically instantaneously available when required by sudden overload.

25 Our governing mechanism broadly comprises means positioned and adapted to control the compressed gas supply to a compressed gas motor of a metal spray gun of a wire feed type and composed of at least one first and one second element, said first element being positioned and adapted to be operatively acted upon by suitable centrifugal speed responsive means to cooperate, by mechanical movement with said second element to thereby restrict the compressed gas supply to the rotor of said motor, and means for 30 variably adjusting the relative position between said second element and the initial position of said first element within a range of mechanical movement of said first element defined by the 35 operating positions of said speed responsive means between minimum and maximum operating speeds of said rotor.

40 In general, the selection of any particular speed responsive device or the particular construction thereof depends, *inter alia*, upon considerations of design, practicability, desired accuracy and sensitivity, intended capacity of the metal spray gun etc., but foremost upon the speed range within which such gun is to operate. The latter factor is of importance as many metal spray guns of the herein mentioned type normally operate within a speed range where the maximum operating speed is in excess of 200% of the 45 minimum operating speed.

Within the preferred embodiment of our invention, therefore, cognizance is taken of the fact that the rotor of the gun must be governed accurately with a sensitive speed governor allowing for variations in speed at which it must be governed over a wide range of operating speeds. For instance, the speed range for the active operation of one particular gun of this type may be from 6,000 revolutions per minute (100 R. P. S.) to almost 40,000 revolutions per minute (666 R. P. S.). This is a speed increase from lowest to highest usable speed of over 500%. With any governor utilizing centrifugal force, this condition presents a particularly acute problem because of the fact that centrifugal force varies as the square of the rotating speed. This means that if the ordinary centrifugal governor were added to the rotor of a metallizing gun, which operates through a 6 times speed range, the force operating on the governor weights 20 would vary 36 times from lowest to highest speed and a mechanical movement actuating the governor mechanism would be subject to equally great variations so that it is in such case practically impossible to obtain the necessary sensitivity at each and every speed throughout the range. In a specific case, for instance, if the total movement of the governing mechanism, which controls the speed, is .150" between lowest and highest operating speed of the gun and if, a change from low speed to one tenth higher speed produces a movement of .075" of the governing mechanism then the remaining nine tenths of the speed range could only actuate the mechanism through a total movement of .075" which is the remaining distance. This would be an insufficient movement of the mechanism for so wide a speed range, and the governor would not be sensitive, nor perform satisfactorily.

The governor in accordance with our preferred construction makes it possible for the first time to utilize a governor of the centrifugal type to govern the rotor of a metal spray gun of the wire feed type through a wide speed range whereby the governing action, i. e., the mechanical movement of the actuation mechanism is substantially approximately proportional to the change in speed of the rotor throughout the speed range covered by the governor.

The principle underlying the preferred construction of the centrifugal speed responsive mechanism in accordance with the invention will be more fully understood from the diagrammatic representation, shown in Fig. 18, in which Y is the axis of rotation of a governor element having an arm of the length l and carrying at its end the mass M and pivotally connected at X . R is the distance of M from the axis of rotation Y , and ϕ the angle of deflection of the arm l from the axis of rotation Y .

When the governor element rotates at an angular velocity ϕ about its axis Y , centrifugal force acts on the mass M in a direction perpendicular to the axis Y . This force is indicated by the vector arrow F . The force F can be considered to be resolved into a component force indicated by vector arrow C , perpendicular to the arm l , and a component force indicated by the vector arrow S , in the direction of the arm l . The component force C tends to deflect the arm and, assuming the latter to move outwardly against a spring resistance, indicated by the vector arrow P , is balanced by the spring resistance

P at any given operating position of l . This spring resistance P is defined by $K\phi$ in which K is the unit spring force in dynes for unit angular deflection of l i. e., for each degree of deflection of l , through a given range of deflection or corresponding value of ϕ .

$$F = M\omega^2 R \quad (1)$$

$$\omega = \frac{2\pi}{T} \quad (2)$$

T is the time required for one revolution and may be expressed in R. P. S.

$$T = \frac{1}{R.P.S.} \quad (3)$$

$$\omega = 2\pi R.P.S. \quad (4)$$

$$R = l \sin \phi \quad (5)$$

$$F = M 4\pi^2 \frac{2}{R.P.S.} l \sin \phi \quad (6)$$

$$C = F \cos \phi \quad (7)$$

$$C = M 4\pi^2 \frac{2}{R.P.S.} l \sin \phi \cos \phi \quad (8)$$

$$2 \sin \phi \cos \phi = \sin 2\phi \quad (9)$$

$$C = M 2\pi^2 \frac{2}{R.P.S.} l \sin 2\phi \quad (10)$$

as C is balanced by the spring resistance of arm l .

$$K\phi = M 2\pi^2 \frac{2}{R.P.S.} l \sin 2\phi \quad (11)$$

assuming $l=1$ and $m=1$

$$K\phi = 2\pi^2 \frac{2}{R.P.S.} \sin 2\phi \quad (12)$$

(ϕ may be expressed in radians or degrees if K is appropriately chosen).

Assuming as a representative example an operating range of from 6000 to 40,000 R. P. M. (100 to 666 R. P. S.) and a total maximum deflection of 88° at a maximum speed of 666 R. P. S., the value of K for equilibrium at that deflection may be found by inserting the various values in Equation 12 resolved for K .

$$K = \frac{2\pi^2 \frac{2}{R.P.S.} \sin 2\phi}{\phi} \quad (13)$$

$$K = \frac{2\pi^2 \frac{2}{666} \sin 176^\circ}{88^\circ} = 883.7 \quad (14)$$

Having established the unit value K for each degree of deflection through a range from 0° to 88° with a maximum of 666 R. P. S. at 88° , Equation 12 may be resolved for the determination of R. P. S. for different deflections of l or values of ϕ .

$$R.P.S. = \sqrt{\frac{K\phi}{2\pi^2 \sin 2\phi}} \quad (14)$$

The R. P. S. values obtained for different values of ϕ are listed in the following Table I.

Table I

[Deflection range 0° - 88°]

ϕ	0	10	20	30	40	50	60	70	80	85	88
R. P. S.	0.118	118.02	124.53	134.8	150.8	176.1	220.8	331.1	468.1	666	

When plotting the curve defined by Equation 12

in accordance with the values given in Table I the curve has a slope as demonstrated by curve I in Fig. 1.

When using instead of an arm controlled by a spring force acting throughout the entire range of 0° to 88° , an arm controlled by a spring force acting through a range beginning with a predetermined initial position at the angle γ of the arm l with respect to the axis of rotation Y , a different value for K controls. This value is defined by Equation 13 except that the value for $\phi = (88^\circ - \gamma)$.

$$K = \frac{2\pi^2 R.P.S. \sin 2(88^\circ - \gamma)}{(88^\circ - \gamma)} \quad (15)$$

The values of K obtained for different values of γ are listed in the following Table A.

Table A

γ	40	50	60	70	75
K	16,200.6	20,464	27,772.5	42,909.2	59,817.7

The R. P. S. values in accordance with Equation 14 for predetermined angles of γ are determined by

$$R.P.S. = \sqrt{\frac{K(\phi - \gamma)}{2\pi^2 \sin 2(\phi - \gamma)}} \quad (16)$$

The R. P. S. values for different values of ϕ and for each series with constant predetermined values for γ and corresponding constant values for K are listed in the following Tables II, III, IV, V, and VI.

Table II

[Deflection range γ to 88°] $\gamma = 40^\circ$

ϕ	40	41	50	60	70	80	85	88
R. P. S.	0	28.8	91.3	137.7	195.7	309.8	461.2	666

Table III

[Deflection range γ to 88°] $\gamma = 50^\circ$

ϕ	50	51	60	70	80	85	88
R. P. S.	0	32.56	109.41	179.6	309.8	461.2	666

Table IV

[Deflection range γ to 88°] $\gamma = 60^\circ$

ϕ	60	61	70	80	85	88
R. P. S.	0	40.7	147.9	286.8	450.0	666

Table V

[Deflection range γ to 88°] $\gamma = 70^\circ$

ϕ	70	71	75	80	85	88
R. P. S.	0	59.6	147.9	252.9	434.8	666

Table VI

[Deflection range γ to 88°] $\gamma = 75^\circ$

ϕ	75	76	80	85	88
R. P. S.	0	80.3	210.5	417.7	666

10 The curves plotted for each series of values for ϕ and R. P. S. given in the foregoing tables, are illustrated in Fig. 15 as II, III, IV, V and VI corresponding respectively to the tables of the same designation.

15 Analyzing these curves, it will be seen that in each curve there is a section or sections the slope of which roughly approximates a constant, i. e., for approximately equal increments in R. P. S. there are approximately uniform increments in angular deflection of the arm l . This permits the speed governing mechanism to be variably adjusted to any desired R. P. S. throughout the R. P. S. range defined by the particular constant slope curve section and to thereby attain an approximately accurate, uniform and sensitive speed governing operation.

20 It will be seen however that the different constant slope curve sections of the various curves differ in the R. P. S. range covered by such curve section. Thus, for instance, the section of curve

25 I between 10° and 70° angular deflection, though roughly approximating a constant in its slope, has a very steep pitch with respect to the abscissa and covers for a total of 60° deflection an R. P. S. range of only from 115 to 220 R. P. S. that is a total R. P. S. range of only 105 R. P. S. As to the curve sections of curve I between 70° and 85° angular deflection and 80° and 88° angular deflection, the pitch with respect to the abscissa of these sections is not as steep. As to the section between 70° and 85° angular deflection of curve I, there is an R. P. S. range of 220 to about 465, i. e., a total R. P. S. range of only 245 R. P. S. for a total deflection of 15° . With respect to the section of curve I between 80° and 88° angular deflection, the R. P. S. range is from 330 to 666 or a total of only 333 R. P. S. for 8° deflection.

30 It is thus seen from the analysis of curve I that there is no single constant slope section in this curve defining anywhere an R. P. S. range covering in excess of 200% speed variations. Though a governor element operating within the range defined by curve I may be used within the limitations inherent therein, such governor element is ordinarily not satisfactory in the case of a metal spray gun of the gas blast type normally operating within a speed range where the maximum operating range is in excess of 200% of the minimum operating range.

35 40 The dotted outlines of the various curves represent the plotted slopes below minimum operating R. P. S. i. e., 100 R. P. S. of the device in accordance with this illustration.

45 50 Analyzing the curves based on a predetermined initial angular position of the arm l (curves II, III, IV, V and VI) it will be seen that curves II and III do not possess any section above minimum operating R. P. S. of 100 for which the slope roughly approximates a constant and which defines an R. P. S. range covering in excess of 200% speed variation. In curves IV, V and VI, it will be seen that these curves roughly approximate a constant all the way between the minimum operating R. P. S. of 100 and the maximum operating R. P. S. of 666 which is equiva-

lent to an R. P. S. range covering in excess of 500% speed variation. In these cases the approximation of a constant increases with the increase in the predetermined initial angular position of the arm with respect to the axis of rotation and, although for practical operation a predetermined angle of 70°, as exemplified by curve IV, will give satisfactory results, higher angles as illustrated by curves V and VI are preferred. Although the constancy of slope improves with higher initial angles, it has been found that the governing element with too high a predetermined initial angle may lose sensitivity. For best results an arm having its spring set for a predetermined initial angular position between 70 and 80° and preferably at approximately 75° with respect to its axis of rotation is preferred. This is exemplified in its operating range by curve VI. "Initial position" or similar expression as used herein in connection with the arm or arms in accordance with our invention is intended to connote the angular position assumed by the arm or arms at zero speed.

Although in the foregoing equations and the various curves illustrated in Fig. 15 a minimum operating range of 100 R. P. S. and a maximum operating range of 666 R. P. S. with an assumed maximum deflection of 88° have been selected, it is understood that these values are merely used by way of exemplification of the principles underlying the preferred embodiment of our invention. The results are not substantially different and the same type of curves result if other values or ranges are substituted for those hereinabove used.

The variable speed governing mechanism, in accordance with the preferred construction of the invention, for a metal spray gun of the wire feed type, having a compressed gas motor, comprises at least one arm, rotatable with the rotor of such motor and centrifugally deflectable for angular deflection with respect to its axis of rotation, against spring resistance, and a predetermined initial position and preferably from a predetermined initial position of at least 60° with respect to such axis; speed control means, composed of at least one first and one second element, the first element being positioned and adapted to be operatively acted upon by the arm or arms upon centrifugal actuation thereof to cooperate, by mechanical movement, with the second element to thereby restrict the compressed gas supply to the rotor of the motor; and means for variably adjusting the relative position between the second element and the initial position of the first element within a range of mechanical movement of the first element defined by the angular deflection of the arm or arms between minimum and maximum operating speeds of the motor. The "initial position" of the first element of the speed control means referred to herein, designates that position of such first element as is controlled by the deflectable arm or arms at its or their initial position.

The metal spray gun of the gas blast type embodying our invention does not require any change of gearing. The same is capable of maintaining any number of practical wire feeding speeds and may be shifted from one speed to another by a simple adjustment of the preferably manual control means. Furthermore, the motor or turbine of such metal spray gun is at all times maintained in a stable operating condition. The particular construction in accordance with the preferred embodiment of our invention permits the use of these metal spray guns under sub-

stantially stable operating conditions, over a much wider range of wire feed speeds than is otherwise possible.

The invention will be more fully understood and further objects thereof will appear from the following description read in conjunction with the drawings in which:

Fig. 1 is a side view of a metal spray gun illustrating one embodiment of a construction in accordance with the invention;

Fig. 17 is a view of a central section of the showing of Fig. 16 on the plane indicated by XVII-XVIII, and

Fig. 18 is a diagram illustrating the principle underlying the preferred construction of the centrifugal speed responsive mechanism in accordance with the invention.

The centrifugally actuatable arm element in accordance with our preferred structure may be any one or a multiple number of suitable spring force controlled arm or arms; we prefer a construction, however, where the arm element is a spring element which has for instance one or more spring arms, i. e., arms made of spring material set at the desired predetermined initial angle.

In case of a substantially rigid arm, we prefer to obtain deflectability thereof by pivotally mounting the arm with respect to its axis of rotation. When using one or more spring arms pivotable mounting thereof may be dispensed with as a rule since these as such will permit satisfactory deflection.

Referring to the drawings 1 (Fig. 2) indicates the inlet for oxygen or other combustible supporting gas, 2, the inlet for acetylene or other combustible gas, and 3, the inlet for air or other gas for atomization of the metal, projection of

the metal spray and driving of the turbine. When plug 4 of valve 5' is in the position shown; each of the inlets registers with a corresponding hole in the plug, these holes being indicated by numerals 5, 6 and 7 respectively. In this position, oxygen flows through duct 10 into duct 11. The combustible gas flows through duct 12 to mix with the oxygen in duct 11 and the air flows through duct 15 into chamber 16 and also flows through the side connection 17 into turbine manifold 19. As handle 8 is slightly turned from the off position, which is at a right angle to the showing in Fig. 2, ducts 5, 6 and 7 in plug 4 can be so positioned that at first a relatively small amount of combustible gas passes into duct 11 and thence to the burner outlet to enable the burner to be lighted while a small amount of air passes simultaneously into manifold 19 to enable the turbine to come up to speed. Alternatively all the valve passages may be opened wide. The rates of flow of the gases, however, must be then so adjusted as to establish favorable lighting conditions which are different from the conditions as to gas flow and air blast obtaining when the gun is in operation. The washer 20 (Fig. 3) defines a hole 21 of rectangular cross-section which fits closely the shank 22 (or corresponding section) (Fig. 2) of the plug 4. The washer 20 is formed with the depression 23 (Fig. 3). This washer is spring pressed, and this depression slips onto the head of pin 24 when handle 8 is in the correct position for lighting the burner. This offers sufficient resistance to indicate to the operator the lighting position. After the burner has been lighted a slight pressure against handle 8 forces the depression 23 out of engagement with the head of the pin 24. A further movement of handle 8 causes oxygen to flow through duct 10 which establishes a melting flame with the ignited gas and the final movement of handle 8 to the position shown in Fig. 2 permits air to flow into duct 15 and thence into chamber 16 and into the interior of air tip 41 under pressure to project the sprayed metal upon the surface to be covered.

The construction of that part of the gun by which the rod or wire is melted and projected will be explained by reference to Fig. 9. The wire 37 moves forward to guide 31 and through duct 32 to the interior 33 of the burner tip 34. The mixture of air and oxygen move forward through the duct 11, which is immediately behind duct 32 (the arrangement is shown in Fig. 2) and into the annular space 35. From this annular space 35 the combustible mixture moves forward through a number of holes to be discharged through convergent orifices against the wire. This forms a zone of gases undergoing combustion, whereby the wire 37 melts as rapidly as it is progressively advanced into the zone, for which reason this zone is referred to as a melting zone. The air from the chamber 16 advances through the annular space 40 surrounding burner tip 34 and is projected by air nozzle 41 in such a way as to sub-divide and propel the molten metal. The air tip 41 is threaded to the outer shell 42 of the burner so that the orifice 43 defined by conical interior of air tip 41 and conical exterior of burner tip 34 may be adjusted with corresponding variations in the characteristics of the air blast. When a satisfactory adjustment has been made, the tip 41 is locked in position by the lock nut 44. It will be noted that the air in passing forward from the chamber 16 goes through the constricted annular space 45 which exerts a definite control over the volume of air passing. As a result of

this construction and the orifice effect thereby created, the adjustment of air tip 41 modifies the characteristics of the air blast without so great a modification of the volume of air passing thereto as would otherwise result, which is decidedly advantageous in the adjustment and operation of the gun.

The wire 37 (Fig. 9) enters the gun through the annular guide 50 of hardened material in which 10 is the duct 51. The upper and lower surfaces of the wire are engaged respectively by the burs 52 and 53. Bur 53 is carried by shaft 54, which shaft is driven by an air turbine through suitable intermediate gearing which will be hereinafter described. Shaft 54 (Fig. 4) also drives the gear 55 in mesh with gear 56, which in turn drives the upper bur 52. Both gear 56 and bur 52 are secured to the tubular member 57 which rotates on the spool 58 carried by pin 59 (Fig. 4). The 20 screw 59 is carried by the saddle 60 and this saddle is pivotally secured (Fig. 9) to frame 61 of the gun by the hinge 62. When cap 65 is turned the threaded end 66 of the screw 67 advances into the threaded member 68 which is a part of frame 25 61 and the spring 70 exerts pressure on the saddle 60, thereby forcing the upper bur 52 toward the lower bur 53 and thereby causing the burs to engage and advance the wire 37. Conversely, when cap 65 is turned in the reverse direction, 30 pressure of spring 70 on saddle 60 is released and the burs move freely without engaging and advancing the wire.

The shaft 54 (Fig. 4) which drives bur 53 is mounted in ball-bearings 70 and 71. Bearing 70 is held in frame 61 and bearing 71 is held in the 35 housing 72 which is attached to frame 61. The shaft 54 is driven by the worm gear 72, which in turn is driven by the worm 74, carried by the shaft 75. Shaft 75 (Fig. 10) is carried by ball-bearings 76 and 77 mounted in the housings 72. 40 Shaft 75 is in turn driven through the worm gear 78 by the worm 79. The worm 79 (Fig. 5) is integral with the shaft 602 carried by bearings 85 and 86. Bearing 85 is mounted in housing 72 and bearing 86 is mounted in the cap or cover 90 of the turbine 91.

Turbine 91 (Fig. 5) includes the turbine rotor drum 95 secured to shaft 80. Details of the blading 100 are apparent from Figs. 7 and 8. Fig. 5 illustrates a view of part of the governor construction showing the spring arms 200 carrying the weight buttons 202 mounted on the turbine rotor drum 95. The arrangement of the turbine blading 100 is illustrated in Fig. 7 and is further exemplified in Fig. 8 showing a view of the turbine rotor drum 95 at right angles to the showing in Fig. 7. As evident from Fig. 6, cover 90 includes the mounting 101 for the ball-bearing 86 and three ridges 102 (only two of which are illustrated) radially arranged about mounting 101 on the interior surface of the cover. The washer-shaped member 103 is made of fine wire mesh and rests directly upon ridges 102. The washer 104 rests directly on the washer 103. The washer 104 has the perforations 105 (Fig. 6A). The washers 103 and 104 are held in contact with each other and with the ridges 102 by the strips 106, which in turn are secured to the ridges 102 by the screws 107. One result of this construction is that the exhaust from the turbine flows through perforations 105 in the washer 104, thence through the openings in the fine screen of which washer 103 is composed, and thence through exhaust ports 110, in cover 90 (Fig. 6 and Fig. 1) thereby resulting in more quiet operation of the turbine.

Bent clip 207 (Fig. 5) performs the double function, first of providing a driving means through the ears 209, the buttons 202, the spring 200 and the rotor 95. The other function is that of absorbing by its resiliency the pounding action of weight buttons 202. When operating at high speeds, there is a natural tendency for the weight buttons 202 which are mounted on the ends of spring arms 200 to enter into a vibratory motion. This motion is quickly absorbed by the resiliency of the arms of bent clip 207. Fig. 12 is a face view of the bent clip structure showing details of the clip 207 carrying the ears 209 and secured by screws 208 to hub 601 (Fig. 5). It will be understood that bent clip 207 may be eliminated, however, if desired.

Shaft 602 has a slot 301 which is wide enough to permit space for pin 300 and which is long enough, parallel to the axis of the shaft, to permit considerable longitudinal movement of the hub 601, along the shaft when pin 300 is in place extending through the slot 301. Hole 302 is centrally located in shaft 602 and extends from its end past slot 301. Located in hole 302 is pin 303 which is fitted as to be freely slidable in hole 302. One end of pin 303 extends beyond the end of shaft 602 and is smooth and rounded off on this extending end. Valve plunger 304 is slidably mounted in housing 603 and is forced in the direction toward the shaft 602 by the action of coil spring 305 which acts against pin 306 in one end of valve plunger 304. Threadedly mounted in housing 603 is valve body 307 which has threads 308 and finger wheel 309 and valve seat 310. Nut 311 holds packing material 312 against the thread 308 to prevent leakage of air around the threads. Air passage 313 is provided and leads from the air duct 19 to the space 314 between the valve body 307 and the housing 603. Hole 315 through the side of the valve body 307 permits passage of air from space 314 to space 316. When valve plunger 304 is not in contact with valve seat 310, air can pass from chamber 316 into chamber 317 which surrounds the end of the valve plunger 304. Air passage 318 connects space 317 with the short duct 319. Turbine air jet 604 extends from short duct 319 to the surface of housing 605 at such an angle that air emerging from jet 604 impinges against turbine blades 100 to cause turbine rotor 95 to rotate.

In operation the supply of air for operating the turbine enters through duct 19 as previously described. From duct 19 the air flows through passage 313 into space 314, through hole 315 into space 316. From space 316 the air passes between the valve seat 310 and the face of the valve plunger 304 into the space 317. Thence it goes through the passage 318 into the short duct 319 and emerges through turbine jet 604 causing turbine rotor 95 to rotate. As turbine rotor 95 increases in speed, the governor weight buttons 202 move out approximately parallel to the axis of shaft 602 in a direction away from the turbine rotor 95. These buttons 202 which contact the ends of spring clip 207 cause hub 601 to move along the shaft 602 in a direction away from the rotor 95. As pin 300 travels along the shaft with the hub 601, it forces pin 303 to press against the end of valve plunger 304 causing valve plunger 304 to approach valve seat 310. As valve plunger 304 approaches valve seat 310 the air supplied to jet 604 is restricted thus reducing the energy supplied to turbine rotor 95. Consequently at a predetermined speed the air flow will be sufficiently restricted to prevent a further increase of the

speed of turbine rotor 95 and the rotor will operate at this predetermined speed. The operating speed of rotor 95 is predetermined or selected either in advance or during operation by turning the thumb wheel 309 of valve body 307. This screws the valve body 307 in and out on the thread 308 causing the valve seat 310 to get closer to or farther from the face of valve plunger 304. When more speed is desired, the valve body is turned in a direction to provide more space between the seat and plunger and when it is desired to reduce the speed, it is turned in the opposite direction thus providing less space between the valve seat and valve plunger.

Once the speed has been predetermined by the adjustment of thumb wheel 309, the rotor 95 will maintain a speed which is nearly constant. If, for any reason, an increase of load should be applied to the mechanism, as for instance by a kink in the wire being fed then at first the speed of rotor 95 will be slightly reduced. After a very slight reduction in speed, however, the governor weight buttons 202 will move slightly toward the rotor permitting spring 212 to force hub 601 along shaft 602 toward rotor 95. This permits pin 303 to move back and hence spring 305 will move plunger 304 away from valve seat 310. This will permit more air to flow between the valve seat and the plunger and through the passage 318 and 319 to the jet 604. Hence more power is supplied to the rotor to overcome the increase in load and prevent further reduction in speed. Only a very slight reduction in speed is necessary to cause the governor to operate. The end of valve plunger 304 is made relatively large and the passage 316 in the valve seat is made relatively large so that a very slight lateral movement of the plunger 304 is sufficient to cause a large adjustment in the amount of air which can pass between the valve seat and the plunger. Only a very small motion of the governor weight 202 is required to provide a relatively large additional amount of energy in the form of air energy to act on turbine rotor 95. If for any reason the load on the operating mechanism should suddenly become less, then the turbine rotor 95 would speed up slightly. However, even a relatively slight increase in speed will be sufficient to cause the governor weight 202 to move against the spring clip 207 causing the hub 601 and pin 300 to move away from the rotor 95 and cause pin 303 to press against the end of valve plunger 304 pressing it closer to valve seat 310. This action would restrict the flow of air to jet 604 and to the turbine rotor 95 and hence prevent further increase in speed. This construction allows for an ample potential supply of energy to the rotor and also prevents any tendency of the rotor to overspeed or run away.

An alternative construction is shown in the illustrations in Figs. 13 and 14. In this embodiment of our invention the governor spring 200 and governor weights 500 are assembled in the same manner as previously described but they are mounted on the reverse side of the rotor so that in the illustration in Fig. 13 the governor spring 200 is mounted on the rotor 95 on the side toward the housing 605. In this case no sliding hub or spring clip are required. Disc 400 is mounted close to and parallel to the face of housing 605. At the center of disc 400 a short hub is provided which is pressed into the center of ball bearing 401. The outside face of bearing 401 is pressed into the housing 605 so that disc

400 can rotate freely about the same axis as that of shaft 602'. A slot 402 is provided in disc 400, as illustrated in Figs. 13 and 14. Fitted into the face of housing 605' is small pin 403. This pin limits the rotary motion of disc 400 to a motion through a small angle so that at each end of this small permissible amount of motion, the motion is arrested by contact of one or the other end of slot 402 against pin 403. A circular groove 404 is provided in the face of housing 605' to provide space for flat coil spring 405. One end of coil spring 405 is bent at right angles to the plane of the spring at 406 and fits into a hole in the housing 605' at the bottom of the groove 404. The other end 407 of flat coil spring 405 is bent at right angles in the opposite direction and fits through a hole provided for it in the disc 400. This spring is so wound as to act between the housing 605' and the disc 400 so as to tend to force it as far as it will go in a counter clockwise direction as viewed in Fig. 14. Slot 402 is cut wide enough so that the disc 400 does not cover the opening of air jet 604' when disc 400 has been forced by spring 405 to the limit of its travel in a counter clockwise direction (Fig. 14). The location of pin 403 with respect to the location of the opening of jet 604' and the length of slot 402 are such that when the disc 400 has been forced in a clockwise direction as far as it will go that part of the disc 400 indicated at 408 will cover up the opening of the jet 604'.

Bearing 71' which is mounted on one end of shaft 602' is slidably fitted in housing 72' and housing 72' is made sufficiently long to permit of a considerable longitudinal motion of shaft 602'. At the other end of shaft 602' bearing 86' is clamped to the shaft by nut 409 and is clamped in a housing 410 by the threaded cap 411. The outside of housing 410 is provided with threads 412 which mate with threads in housing 603'. On the end of bearing housing 410, a thumb wheel 413 is provided. If thumb wheel 413 is turned, the housing 410 is screwed either in or out of the housing 603'; and as the bearing 86' is rigidly clamped in the housing 410 and to the shaft 602' the shaft and the whole rotor assembly are forced either in or out. Hence by turning thumb wheel 413 it is possible to adjust the longitudinal position of shaft 602' and the whole rotor assembly including rotor 95', governor spring 200 and governor weight button 500. The governor weight buttons 500 are made of a sufficient length so that they can contact the face of disc 400.

In operation air is supplied to turbine jet 604' as previously described and emerges from the jet and acts on turbine rotor blades 100' causing the turbine rotor 95' to rotate. As the turbine rotor 95' increases in speed the weight buttons 500 tend to move parallel to the axis of shaft 602' in a direction towards the face of disc 400. When the weight buttons 500 contact the face of disc 400, and exert even a slight pressure against the disc, they cause friction between the disc and themselves and hence tend to rotate the disc 400. The direction in which they tend to rotate the disc 400 is clockwise as viewed in Figure 14 and the friction of the weight buttons 500 against disc 400 tends to rotate it in opposition to flat coil spring 405. As the speed of rotor 95' increases, this rotary frictional force exerted by the weight buttons 500 on disc 400 becomes sufficient to overcome the force of spring 405 and cause the disc 400 to rotate through

5 a slight angle until part 408 of the disc at least partially obstructs the opening of air jet 604'. This obstruction of the air jet by the interposition of part 408 of disc 400 between jet 604' and the turbine rotor blades 100' reduces the air energy supplied to the turbine rotor 95' and no further increase of speed is possible, the turbine rotor 95' will arrive at and maintain a predetermined speed. This speed is predetermined, 10 or may be adjusted during operation by an adjustment of the longitudinal position of the rotor assembly which is effected by screwing the thumb nut 413 either in or out. If more speed is desired the thumb nut 413 will be turned in such 15 a direction as to screw the rotor assembly away from the face of disc 400 and if less speed is required it will be turned in the opposite direction. The farther removed the rotor assembly is from disc 400 the greater speed will have to be attained before the deflection of the spring 200' will be sufficient to permit the governor weight buttons 500 to contact and thus rotate disc 400.

25 Once a speed adjustment has been made, the turbine rotor 95' will maintain its predetermined speed with but slight variations. If for some reason such as a kink in the wire being fed through the metal spray gun, an increased load is imposed upon the turbine rotor 95', then it will 30 slow down slightly. As soon as it slows down even a very small amount, the weight buttons 500 will move away from the disc 400; if they do not actually move away from disc 400, they will at least reduce the pressure which they exert 35 against the disc 400 thus permitting spring 405 to rotate disc 400 so as to produce less obstruction of the air jet 604'. Hence more energy is supplied to turbine rotor 95' to overcome the additional load which was imposed, and no further reduction of speed will occur. If, on the 40 other hand, for any reason less load is imposed on rotor 95', the same will speed up slightly but even the slightest increase in speed will be sufficient to cause governor weight buttons 500 to 45 bear more heavily against the face of disc 400, producing more friction which tends to rotate disc 400 in such a direction as to further obstruct the opening of air jet 604'. As this will reduce the amount of energy available for the turbine 50 rotor 95' no further increase in speed is possible.

55 Although the foregoing description is complete as far as the action of the governor on the energy supplied to the rotor 95' is concerned, with this embodiment of our invention there is an additional governing action which makes for even more sensitivity of performance and more accurate speed control than is otherwise obtained. This further action is based upon small amounts of power absorbed by the governor so as to produce more instantaneous action than is produced 60 by the air control mechanism alone. When less power is demanded of the turbine rotor 95', as explained above, the turbine rotor tends to speed up slightly and hence to force the governor weight buttons 500 more tightly against the face of disc 65 400 causing the rotation of the disc which reduces the air supply. In addition to this action more pressure between the weight buttons 500 and the face of disc 400 causes power to be absorbed by the friction between weight buttons 500 and disc 400. This absorption of power by friction immediately disposes of some of the excess power produced by rotor 95' and hence also helps to prevent an increase in speed. Conversely, as under normal operating conditions,

there is a slight pressure between the weight buttons 500 and disc 400, if the power load on the turbine rotor 95' is suddenly increased, a slight reduction of speed occurs and the weight buttons 500 bear with less pressure against the face of disc 400 as explained above, hence, in addition to the action of the governor on the flow of air, less friction is produced between the weight buttons and the disc, and hence less power is absorbed by friction which additional power is available to help overcome the additional load imposed upon the turbine rotor 95'.

In this embodiment of our invention therefore, the power absorption principle has been utilized to its best possible advantage in addition to the principle of control of the input energy to the turbine rotor.

As aforementioned, the speed governing mechanism in accordance with our preferred construction broadly comprises a first element, capable of mechanical movement induced by the operation of the arm element, and a second element, cooperating with the first, to effect any desired speed variably adjustable within the entire speed range. Thus, for instance, specifically referring to Figs. 1 to 12, the first element comprises valve plunger 304, operated by the movement of the spring arms 200 by way of the buttons 202, clip 201, hub 601 and pins 300 and 303. The second element in this case is valve seat 310 of valve body 307 variably adjustable within the range of mechanical movement of the valve plunger 304 as controlled by the deflection of the spring arms 200 between minimum and maximum speeds of the rotor 95'. Referring to Figs. 13 and 14, the first element comprises friction buttons 500 operated by the deflection of the spring arms 200; the second element in this case is the disc 400. In this instance the initial position of the first element, i. e., the friction buttons 500 is variably adjustable with respect to the second element or disc 400 by means of the adjustment of the entire rotor assembly within the range of mechanical movement of the friction buttons 500 as controlled by the deflection of the spring arms 200 between minimum and maximum speeds of the rotor 95'.

As aforementioned, the governing arm carrying the weight buttons may be a substantially rigid arm which is preferably pivotally mounted. Referring to Figs. 16 and 17, the rigid arm 701 is shown mounted on rotor drum 700 and pivoted to the drum with pivot pin 702. Weight buttons 703 are mounted on the end of the arm 701. Spring resistance from a predetermined initial position of the arm is provided by spring member 704 attached to rotor drum 700 by screw 705 and bent to contact arm 701. In operation, as the centrifugal force of the weight buttons 703 tends to move arm 701 and cause it to assume a position more nearly perpendicular to the axis of the rotation of rotor drum 700, spring 704 opposes this motion and establishes the position of weight buttons 703 for any given speed of rotor drum 700.

Our invention is not limited to the construction of a spray gun illustrated in the foregoing examples and may be used in connection with any other suitable gun construction of the wire feed type, including those having other heating or melting means for the wire, such as an arc or the like and further including those constructions of this type in which multiple wires are fed to the heating zone.

Although within the preferred embodiments exemplified in the foregoing figures the speed

control mechanism is illustrated in connection with a motor of the air turbine type, it is within the scope of our invention, to use our novel speed control construction to govern other types of compressed gas motors in wire feed type metal spray guns.

The present application is a division of our co-pending application Serial No. 421,196 filed December 1, 1941, and broadly covers a centrifugally responsive speed governing mechanism having speed control means effecting speed control of a rotor of a metal spray gun of the wire feed gas blast type by regulating the compressed gas supply to the turbine of such metal spray gun; our co-pending application Serial No. 421,194 covers a speed governing mechanism for such rotor having speed control means comprising speed control elements cooperating by mechanical movement and actuated by centrifugally operated and angularly deflectable arms; and our co-pending application Serial No. 421,195 covers a speed governing mechanism for such rotor effecting speed control of such rotor by friction elements cooperating by mechanical movement and actuated by centrifugal means.

The foregoing specific description is for purposes of illustration and not of limitation, and it is therefore our intention that the invention be limited only by the appended claims or their equivalent wherein we have endeavored to claim broadly all inherent novelty.

We claim:

1. A variable speed governing mechanism for a metal spray gun construction of the wire feed type, having a compressed gas motor, comprising first means rotatable with the rotor of said motor and centrifugally movable with respect to their axis of rotation, against spring resistance, from a predetermined initial position with respect to said axis, second means, composed of at least one first and one second element, said first element being positioned and adapted to be operatively acted upon by said first means upon centrifugal actuation thereof, to cooperate, by mechanical movement and frictional contact with said second element to thereby actuate said second element to restrict the compressed gas supply to the rotor of said motor, and means for variably adjusting the relative position between said second element and the initial position of said first element within a range of mechanical movement of said first element defined by the centrifugal movement of said first means between minimum and maximum operating speeds of said rotor.

2. A variable speed governing mechanism for a metal spray gun construction of the wire feed type, having a compressed gas motor, comprising at least one arm, rotatable with the rotor of said motor and centrifugally deflectable for angular deflection with respect to its axis of rotation, against spring resistance, from a predetermined initial position with respect to said axis, speed control means, composed of at least one first element positioned and adapted to be operatively acted upon by said arm upon centrifugal actuation thereof, at least one second element positioned and adapted to be operatively acted upon against spring force by said first element upon actuation thereof to thereby restrict the gas supply to said rotor between said rotor and the compressed gas jets therefor and means for variably adjusting the relative position of said first element with respect to the initial position of said second element.

3. A variable speed governing mechanism in accordance with claim 2, in which said first and second elements cooperate by mechanical movement and frictional contact to thereby restrict the gas supply to said rotor.

4. A variable speed governing mechanism for a metal spray gun construction of the wire feed type, having a compressed gas motor, comprising at least one arm, rotatable with the rotor of said motor and centrifugally deflectable for angular deflection with respect to its axis of rotation, against spring resistance, from a predetermined initial position with respect to said axis, speed control means, composed of at least one first element, rotatable with said arm, and positioned and adapted to be operatively acted upon by said arm upon centrifugal actuation thereof, so as to limitedly move, against the force of a spring, to thereby restrict the gas supply to said rotor between said rotor and the compressed gas jets therefor and means for variably adjusting the relative position of said first element with respect to the initial position of said second element.

5. A variable speed governing mechanism in accordance with claim 4 in which said arm is centrifugally deflectable from a predetermined initial position of at least 60° with respect to said axis.

6. A variable speed governing mechanism in accordance with claim 4 in which said arm is centrifugally deflectable from a predetermined initial position of from 70° to 80° with respect to said axis.

7. In a variable speed governing mechanism for a metal spray gun construction of the wire feed type having a compressed gas motor, the improvement in speed control means by power input control comprising a disc element limitedly

rotatable against spring force and carrying an obstruction normally substantially out of registry with the compressed gas jet for the rotor of said motor, a friction element, rotatable with said rotor, positioned and adapted to be operatively acted upon by centrifugal speed responsive means to move said obstruction by frictional engagement with said disc element from limitedly to completely into said registry, and means for variably adjusting the relative position between said disc element and initial position of said friction element within a range of mechanical movement of said friction element defined by minimum and maximum operating speeds of said rotor.

8. In a variable speed governing mechanism for a metal spray gun construction of the wire feed type having a compressed gas motor, the improvement in speed control means by power input control comprising an axially slideable rotor assembly for said motor, having at least two substantially coaxially aligned symmetrically arranged, radial spring arms, carrying weights adjacent the free ends thereof, said arms being mounted on said rotor and centrifugally deflectable for angular deflection with respect to their axis of rotation, against spring resistance, from a predetermined initial position of from 70° to 80° with respect to said axis, a disc, and rotatably mounted substantially coaxial with said axis, a cut-out in said disc, a spring normally holding said cut-out in substantial registry with the compressed gas jet for said rotor against rotation in the direction of said arms, and screw means for variably adjusting the position of said rotor assembly with respect to said disc.

ARTHUR P. SHEPARD.
